UNITED STATES PATENT OFFICE.

JOHN B. THOMS, OF KNOXVILLE, TENNESSEE.

VAT FOR LEACHING BARK.

SPECIFICATION forming part of Letters Patent No. 645,439, dated March 13, 1900.

Application filed May 1, 1897. Renewed January 16, 1900. Serial No. 1,686. (No model.)

To all whom it may concern:

Be it known that I, JOHN B. THOMS, a citizen of the United States, residing at Knoxville, in the county of Knox and State of Tennessee, 5 have invented a certain new and useful Vat for Leaching Bark, of which the following is a specification.

My invention relates to a vat for leaching bark, and it may be used for filtering sugar, 10 as will be hereinafter described.

Heretofore in the vats and processes generally used for leaching bark there has been a great waste of the bark, owing to the poor circulation of the liquid through the bark in 15 the vat, as well as the means for drawing off the liquid. The object of my invention is to overcome these objections, to prevent the waste of the bark, and to obtain a larger percentage of the tanning properties from the 20 bark and also a heavier liquid, which is very desirable in tanning. I accomplish this by providing a central draw-off pipe and a surrounding annular series of draw-off pipes, seven in 25 number, which extend from a common central discharge-pipe and have inlets which are evenly distributed throughout the chamber in the base of the vat, so that the same amount of liquid will be drawn off from each of these 30 inlets, and in order to obtain the best results I have the draw-off pipes all of the same diameter or capacity and their combined areas in cross-section equal to the area in cross-section of the single discharge-pipe with which 35 they communicate. I have also discovered in practice that to obtain a perfect circulation the bark should always be covered, so as to hold it in suspension and prevent the bark becoming packed, and the space or chamber beneath the bark, with which the draw-off 40 pipes are connected, should always be kept filled.

My invention consists of a suitable vat of any desired dimensions, provided with a perforated false bottom, which is covered with 45 bagging to prevent the finely-ground bark getting in the space between it and the bottom of the vat, and a central draw-off pipe and a surrounding annular series of draw-off pipes of the same diameter and combined area equal to 50 the area of the single discharge-pipe with which they communicate, and having their in-

lets evenly distributed in the chamber or space beneath the perforated false bottom.

My invention also consists of certain other details of construction that will be herein- 55 after more fully described and specifically claimed.

In order that my invention may be fully understood, I will proceed to describe the same with reference to the accompanying drawings, 60 in which—

Figure 1 is a vertical axial section taken on the line 1 1, Fig. 3, looking in the direction of the arrows, showing one form or arrangement of parts in a vat constructed in accordance with my invention. Fig. 2 is a vertical axial section taken on the line 2 2, Fig. 4, looking in the direction of the arrows, showing another or modified form of the invention. Fig. 3 is a horizontal section taken on the line 70 3 3, Fig. 1, looking in the direction of the arrows. Fig. 4 is a horizontal section taken on the line 4 4, Fig. 2, looking in the direction of the arrows.

In the said drawings, 1 represents a vat, 75 which may be of any size, 2 the bottom thereof, and 3 a perforated false bottom, which is arranged within the vat so as to form the space or chamber 4 between it and the bottom 3 of the vat. The vat, as usual, above the perforated false bottom is filled with tanbark. To prevent this getting into the space or chamber 4, I provide a covering 5, of bagging, straw, or other material, on the false bottom.

6 represents an outlet or discharge pipe for 85 conducting away the liquid obtained from the bark, and fitted to one end of this pipe are a central draw-off pipe 7 and a surrounding annular series of branch or draw-off pipes, having their inlets 7^a communicating with 90 the space or chamber 4. These inlets of the pipes are evenly distributed in the chamber or space and they are all of the same diameter, so as to prevent any uneven discharge from the space or chamber, and thus main- 95 tain an even circulation throughout the vat, and their combined areas in cross-section is equal in capacity to the area in cross-section of the outlet or discharge pipe 6. Several of the branch pipes are provided with the cross- 100 couplings 8, as shown, and two of the ends are closed or stopped by the plugs 9, which ar-

angement allows of a wire to be run through them to remove obstructions and to prevent their being clogged. In order to flush the pipe occasionally, I provide the water-pipe 10, 5 which is connected with the outlet-pipe 6, and 11 represents a draw-off or waste-water cock on one side of the vat to allow the washings to run away to the sewer.

In Fig. 1 it will be seen that I have entered 10 the inlets of the draw-off pipes into the space or chamber between the bottoms through the bottom of the vat, and in Fig. 2 through the bark and false bottom. This latter form is preferable for the reason that I have found 15 the tendency of the water is to channel as it passes through the finely-ground bark if drawn off too rapidly, and with this arrangement this is prevented.

In practice the vat is constantly kept filled 20 with water to the extent shown in the drawings. This will hold the bark in suspension and will prevent the bark from packing, so that the liquid can easily percolate through the bark and keep the space or chamber be- 25 tween the bottoms filled, so that there will be no possible chance of any uneven circulation through the vat, which, as has been above stated, is essential to obtain the most desirable results in leaching. This latter fact is 30 preserved in the drawing off of the liquid, for the inlet of the draw-off pipes are of the same diameter and their combined areas in cross-section is equal in capacity to the area in cross-section of the single discharge-pipe, 35 from which it will be seen that there can be no uneven discharge from any point in the vat. The vertical inlets 7^a have their inner ends located above the bottom of the vat, so as to prevent the settling going off with the 40 liquor.

My device is also particularly advanta-

geous in filtering sugar, and when employed for this purpose bone-black is substituted for the tanbark. The process is the same as in the tanning of bark, and I have found in practice that a lighter-colored liquid can be obtained and a less amount of sweet water when the bone-black is washed. 45

Having thus described my invention, what I claim as new therein, and desire to secure by 50 Letters Patent, is—

1. The combination of a vat having a perforated false bottom providing in connection with the vat a base-chamber for the resultant liquid and a body-chamber in which the bark 55 is immersed in liquid and held in suspension, the discharge-pipe, and the draw-off pipes provided with cross-couplings for cleaning purposes and connected with the discharge-pipe, having their inlets evenly distributed 60 throughout the base-chamber and their combined areas in cross-section equal in capacity to the area in cross-section of the discharge-pipe; substantially as described.

2. The combination of a vat having a perforated false bottom providing in connection with the vat a base-chamber for the resultant liquid and a body-chamber in which the bark is immersed in liquid and held in suspension, the discharge-pipe extending into the body- 70 chamber and the pendent draw-off pipes connected with the discharge-pipe and extending through the false bottom having their inlets evenly distributed throughout the base-chamber and their combined areas in cross- 75 section equal in capacity to the area in cross-section of the discharge-pipe; substantially as described.

JOHN B. THOMS.
